Geo. P. Kimmel.
ATTORNEY.

UNITED STATES PATENT OFFICE.

IRA S. FINLEY, OF COLUMBUS, OHIO.

DOOR JAMB.

Application filed June 11, 1928. Serial No. 284,620.

This invention relates to door jambs and more particularly to devices of this character which have embodied therewith adjustable means shiftable toward, or from the door to compensate for varying widths of the latter.

It frequently occurs that doors, when constructed of very dry wood, will swell, due to absorption of moisture after same has been put up, to such a degree that it is impossible to close same. This necessitates removing the door from the frame and planing off the free edge thereof sufficiently to permit it to pass within the jamb after the door is replaced in the frame. When a door, which is constructed of unseasoned wood, has been in use a short time, said door very often dries out and shrinks, thus leaving a very large opening between itself and the jamb.

This invention has, for one of its objects, the provision, in a manner as hereinafter set forth, of a door jamb which may be expeditiously adjusted relative to the door for the purpose of remedying the defects set forth in the foregoing paragraph and wherein the means for effecting the adjustment will in no way mar or detract from the appearance of the building in which it is installed.

Another object of the invention is the provision of a device of the aforementioned character which will be simple in construction, strong, durable, efficient in its use, and which may be manufactured at low cost.

Other objects of the invention will be apparent from a study of the following specification, taken in connection with the accompanying drawings, wherein like characters of reference denote corresponding parts throughout the several views:

In the drawings:

Figure 1 is a front elevation of a door jamb constructed in accordance with this invention and showing a part of the supporting frame therefor, a portion of said jamb and frame being shown broken away in section.

Figure 2 is a vertical cross section taken on the line 2-2 of Figure 1.

Figure 3 is an enlarged horizontal cross section, taken on line 3-3 of Figure 1 showing a pair of face casings mounted on the frame.

Figure 4 is an enlarged detail perspective view of the securing plate which is mounted on the frame, and

Figure 5 is an enlarged detail perspective view of the securing plate which is mounted on the jamb.

Referring to the drawings in detail, the reference 1 designates generally a door jamb comprising a pair of vertical side members 2, 3 and an upper cross jamb member 4. The members 3 and 4 are provided, on their inner faces, with conventional stop strips 5 and 6 of less width than said members and positioned centrally thereon.

Reference character 7 denotes an upright portion of a door frame which is immovably secured in a wall (not shown) and to which the member 2 is adjustably secured. To the opposite edges of upright 7, a pair of face casings 7' are secured in a manner to extend inwardly of the frame. At its upper end the upright 7 is connected to one end of the cross member 4, and in conjunction with the vertical member 3, forms a support therefor.

The member 2 is slidably positioned between the face casings 7' in spaced, opposed relation to the upright 7 to which frame said member is adjustably secured in the following manner. The upright 7 and member 2 are provided with a plurality of superposed, spaced, horizontally aligned openings 8 and 9. To the inner face of the upright 7 are secured a plurality of superposed, spaced plates 10 having threaded recesses 11 therethrough. The plates 10 are so positioned that the openings 11 therein will register with the openings 8 in the upright. Secured to the opposing face of the member 2, are a plurality of plates 13, arranged in superposed, spaced relation and having inverted U-shaped passages 14 opening at the lower edges of the plates. The plates 13 are so positioned upon the member 2 that the recesses 14 communicate with the openings 9 in said member. Near their opposite ends, the plates 10 and 13 are provided with openings 12 for the passage of securing screws 12' for anchoring the plates 10 and 13 to the upright 7 and jamb member 2 respectively. As shown in the drawings, the plates 10 and 13 are countersunk in the upright 7 and jamb member 2 so that their outer surfaces will be flush with the opposed faces thereof.

Threaded bolts 15 couple the member 2 and upright 7 together and have slotted heads 16 positioned in the openings 9. The bolts further include reduced neck portions

17 which pass through the passages 14 in plates 13 and are free to rotate therein. The reduced neck 17 of each bolt provides a pair of spaced shoulders 17' which are adapted 5 to oppose the faces of the plates 13. It is to be understood that the neck portions 17 of the bolts 15 are inserted in the passage 14 prior to mounting the plates 13 on the member 2. The bolts 15 are then threaded 10 through the openings 11 in the plates 10 and project into openings 8 in upright 7.

On its inner face the member 2 is provided with a removable stop strip 18 which is positioned centrally thereon and is of the 15 same width as the strips 5 and 6. The strip 18, besides functioning as a door stop, serves to conceal the openings 9 in the jamb member 2 and is secured to said member by screws 19. The upper end of the strip 18 20 abuts the lower face of the strip 5, while the jamb member 2 is formed at its upper end with upwardly extending spaced legs or guides 20 which embrace the strip 5 and abut the lower side of the cross member 4. 25 The lower end of the strip 18 is flush with the lower end of the jamb member 2.

In use, the device functions in the following manner:—

The jamb member 2, having the plates 13 30 and bolts 15 thereon, is positioned between the face casings 7'. The bolts 15 are then threaded through the openings 11 in plates 10, thus drawing the member 2 toward the frame 1 by reason of the shoulders formed 35 by the reduced neck 17 engaging the plates 13, as will be apparent from a study of the drawings. When the member 2 has been adjusted to the desired position, the stop strip 18 is removably secured thereto and 40 the door may then be hung. Should the door shrink or swell after being hung, the trouble may be remedied by simply removing the strip 18, inserting the blade of a screw driver in the slot in heads 16 and screwing 45 the bolts 15 in or out until the member 2 is adjusted to the desired position, after which the strip 18 is replaced. By reason of the legs 20 extending upwardly on each side of the strip 5, said strip acts as a guide for the 50 upper end of the member 2, as will be apparent.

It is thought that the many advantages of a door jamb constructed in accordance with this invention will be readily understood, 55 and, although the preferred embodiment of the invention is as illustrated and described,

it is to be understood that changes in the details of construction may be made which will fall within the scope of the appended claims.

60

What I claim is:—

1. In combination, an upright, a door jamb for connection therewith and comprising a vertical, stationary jamb member having a stop strip thereon, a cross jamb member having a stop strip thereon, disposed at right angles to the vertical member and having one end connected thereto and its opposite end supported on said upright, a shiftable jamb member mounted on the upright having guides on its upper end for engaging the sides of the stop strip on the cross jamb member for the purpose of guiding said shiftable member, and means for supporting the shiftable member from, and 65 adjusting it with respect to, the upright.

65

2. A door jamb comprising vertical, spaced, stationary and shiftable jamb members, said shiftable member having spaced 70 openings, a horizontally disposed stationary jamb member extending between the vertical members adjacent the upper ends thereof, stop strips on the inner sides of said jamb members, guides on the upper end of the shiftable member for engaging the strip on the horizontal member, plates mounted on the shiftable member and having U-shaped recesses communicating with the openings in said member, threaded bolts, having reduced neck portions terminating in an enlarged head mounted in the openings in the shiftable member and rotatably retained 75 therein by the plates, said bolts constituting means for adjustably mounting the shiftable member on a door frame.

80

3. A door jamb comprising opposed, vertically disposed spaced stationary and shiftable jamb members, a cross jamb member positioned therebetween at the upper ends of 85 said vertical members, stop strips secured on the inner faces of the jamb members, guides, comprising spaced, vertical legs carried by the shiftable member and adapted to slidably embrace the stop strip on the cross member therebetween, and means for supporting said shiftable member and for adjusting same toward or from the stationary member.

85

In testimony whereof, I affix my signature hereto.

IRA S. FINLEY.
